DESIGN FOR A CAN TOP

Leonard Eisenberg, New York, N. Y.

Application December 26, 1939, Serial No. 89,139

Term of patent 7 years

To all whom it may concern:

Be it known that I, Leonard Eisenberg, a citizen of the United States of America, residing at 15 Dash Place, New York city, in the county of Bronx and State of New York, have invented a new, original, and ornamental Design for Can Tops, of which the following is a specification, reference being had to the accompanying drawing, forming part thereof.

In the drawing:

Fig. 1 is a sectional view along line 1—1 of Fig. 2 and

Fig. 2 is a top plan view of the can top showing my new design.

I claim:

The ornamental design for a can top, substantially as shown.

LEONARD EISENBERG.
